Primary Examiner — Terry A Wallace(74) *Attorney, Agent, or Firm* — ScienBiziP, P.C.(57) **CLAIM**

The ornamental design for a drop-in ice bucket, as shown and described.

DESCRIPTION

FIG. 1 is a front, right, and top perspective view of a drop-in ice bucket, wherein a top cover is opened, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2 comprising a part of a pipe; and,

FIG. 10 is a front, right, and top perspective view of the drop-in ice bucket, wherein the top cover is closed.

The broken lines shown in the drawings are included for the purpose of illustrating portions of the drop-in ice bucket that form no part of the claimed design.
